APPARATUS FOR ORIENTING WAFERS

James G. Black, Jr., Springfield, Va., assignor to Illinois Tool Works Inc., a corporation of Delaware
Original application Nov. 23, 1960, Ser. No. 71,302, now Patent No. 3,078,335, dated Feb. 19, 1963. Divided and this application Sept. 18, 1962, Ser. No. 224,900
2 Claims. (Cl. 198—33)

This invention relates to apparatus for orienting wafers and more particularly relates to apparatus for orienting thin asymmetrical ceramic wafers and constitutes a division of my patent application entitled "Wafers for Modular Construction," having Serial Number 71,302, filed November 23, 1960, now Patent No. 3,078,335.

In the electrical art, and particularly in electronic apparatus, module assemblies are often provided and usually include ceramic wafer elements made of for example steatite, the wafer elements being generally square, flat and substantially uniform in peripheral dimension and thickness. The marginal edges of the wafers are provided with a plurality of V-shaped notches which are generally equally spaced, and the prior art wafers include one additional U-shaped or V-shaped orientation notch, recess or keyway located symmetrically and centrally between two of the V-shaped notches. These orientation notches and orientating feeder therefor are described in my previous patent application filed October 31, 1955, which is issued as a United States patent on November 24, 1959, and is identified as United States Patent No. 2,914,161. The instant application is concerned with improvements in the orienting feeder which is especially adapted to handle very small sizes of wafers, as well as the wafer per se, and its associated orienting element.

The structure in the above described patent has operated very well for accomplishing orientation of larger size wafers where the wafer size is three quarters of an inch in size or greater. However, with increasing demands for miniaturization of electronic components, new wafer designs and orientation techniques must be provided to handle these smaller size components. In the smaller wafer components (under $\frac{3}{4}$ of an inch) there is a necessity for (a) maximum utilization of the surface area for circuitry, (b) a maximum (or limited) number of symmetrical V-shaped notches in the side edges of the wafer for riser wires to interconnect a plurality of wafers, (c) maximum dielectric distance between riser wire notches, (d) maximum structural integrity consistent with the above, and (e) an orienting configuration which does not interfere with the above requirements. Thus, an orientation notch on the side edge which for obvious reasons must be of a substantially larger dimension than riser notches to permit wafer orientation, becomes undesirable because of the reduction in the mechanical strength of the wafer, the extreme tightness of tolerances required, and the poor use of the total marginal edge space consistent with the maximum number of notches which must be symmetrically arranged on the side edges for later modular assembly techniques. Stated another way, if a U-shaped orientation notch (of the prior art), of larger size than the V-shaped riser notches, is placed on a side edge for orientation purposes, the consequent increase of spacing between adjacent V-shaped riser notches must be increased so that there is sufficient mechanical strength in the wafer, and since the wafer must be adapted for later modular assembly, all V-shaped riser notches must be symmetrically arranged and hence the wafer must be increased in size.

I have overcome these problems by utilization of the corner areas of the essentially square wafers for orientation purposes. The corner areas of the wafers, taught by the prior art, were essentially square neglecting the very

2

slight radius at the corners which is put in for obvious production reasons. Heretofore, the corner areas of the wafers had no particular utility per se. By the particular relief of the corners taught by the instant application, the structural integrity of the wafer is maintained, the spacing of the V-shaped notches in the side edges are at minimum dimensions, and the wafer is well adapted to be oriented by an automatic means which will be later described.

10 It is thus a general object of this invention to provide a new configuration for a dielectric wafer construction of the above described general type and means for utilizing this configuration for orientation.

15 Another object of this invention is to provide a new configuration of orienting means on a wafer which is particularly adapted for small sizes of wafers where space is at a premium, which maintains the desired electrical spacing of the riser wires, and maintains the mechanical strength of the wafer.

20 Another object of this invention is to provide a high speed positive orienting means which will effect orientation of the above discussed wafer in only one of its eight possible positions as it is fed through an orienting device.

25 It is a further object of this invention to provide a vibratory type compact mechanism for orienting wafers as above described which is utilizable as an attachment to an assembling apparatus for the wafers of the claimed construction.

30 The novel features that are characteristic of the invention are set forth particularly in the appended claims. The invention itself, however, both as to its organization and its method of operation, together with additional objects and advantages thereof will best be understood by 35 the following description of a specific embodiment when read in connection with the accompanying drawings, in which:

FIG. 1 is a front elevational view of the novel wafer aligned with a complementary aperture in the orienting mechanism, the arrow on the wafer indicating the direction of movement thereof in the orienting mechanism;

FIG. 2 is a sectional view along line 2—2 of FIG. 1;

FIG. 3 is a view similar to FIG. 1 showing a wafer and an orienting aperture in misalignment, the arrow on the wafer indicating the direction of movement thereof in the orienting mechanism;

FIG. 4 is a view of the wafer orienting mechanism, somewhat semidiagrammatic in form;

FIG. 5 is a view taken along line 5—5 of FIG. 4;

FIG. 6 is a sectional view through the inversion station taken approximately along line 6—6 of FIG. 4;

FIG. 7 is an end view of the wafer illustrating the dimensions of the relieved corners; and

FIG. 8 is a perspective view of the novel wafer.

55 As shown in FIGS. 7, 8 and 1 the novel wafer 10 is essentially thin, flat, and of essentially square configuration. The wafers 10 are generally formed of ceramic material, such as from steatite, the side edges of the wafer are normally formed with a plurality of V-shaped notches 12 in symmetrical arrangement around the periphery of 60 the wafer as shown. For purposes of orienting the wafer by mechanical means in accordance with the present invention, the corners 14 and 16 which are terminal portions of one side edge of the wafers are asymmetrically relieved such that only one position of the eight possible 65 positions that a wafer may assume becomes the orienting position. The wafers are adapted to be later printed with circuitry on the two major faces thereof, and a single oriented position of the wafer affords utilization of both sides of the wafer with different circuit configurations. 70 The particular corner relief that I have found to be most suitable, is to remove a right triangular portion of each

corner, the short leg of the triangle being of a dimension X and the long leg of the triangle being $2X$. The same amount of material is relieved from each of the corners 14 and 16, but in a sense the entire triangular relief has been rotated 90° . Thus, along one edge (the top) as viewed in FIGS. 1 and 3, the relieved corner portions have a total dimension of $3X$, whereas the left hand side edge of the wafer, as viewed in FIG. 1, has been relieved along the corner by a dimension $2X$ and the right hand side of the wafer, as shown in FIG. 1, has a relief that extends along the right hand side edge a dimension X .

The orienting apparatus 18 usable with the above described wafer may be mounted on any suitable supporting frame, the support for the instant apparatus 18 being shown semidiagrammatically. The orienting apparatus 18 is adapted to take a plurality of random oriented wafers from a heterogeneous mass of wafers in a hopper 20 (shown semidiagrammatically) of any suitable type, march the wafers through the apparatus so as to orient the wafers in a single one of their eight possible positions and deliver the oriented wafers to a discharge pickup chute 22 at the other end of the apparatus. The power for causing movement of the wafers 10 along the orienting apparatus is provided by a vibrating mechanism 24 of any suitable well-known type.

The basic part of the orienting feeder 18 comprising a vibrating frame member 28 which has orienting troughs and a reversing mechanism. The central vibrating frame member 28 is elongate in nature and preferably made of relatively heavy plate which is resiliently suspended in a vertical plane with its length inclined at an angle downwardly from the horizontal. A plurality of suitable track means 26a-26h, which are canted at an angle from vertical, are mounted on the side of the central 28 as best shown in FIG. 5. Since the wafer is essentially rectilinear in configuration, it has eight possible positions and eight separate stations are provided. At each station is an aperture or window means 32a-32h of generally complementary shape to the wafer to allow a properly oriented wafer 10 to fall therethrough. The window 32 is slightly wider than a wafer 10 and the top of the window extends slightly higher than the height of a wafer resting on the track means. The track means 26 is provided with an angular portion 30 and a transverse end portion 34 which serves as a support for a non-oriented wafer. It will be noted that the vertical height of end portion 34 is such that in a sense, it covers a lower part of a window and thus serves the function of providing an abutment edge to provide a fulcrum for pivotal movement of an oriented wafer through the window. This is illustrated schematically in FIG. 5. As viewed in FIG. 4, the wafers pass along the tracks from window station 32a down through 32h until they become correctly aligned with an aperture or window in the manner shown in FIG. 1 whereupon they fall through plate 28 on the wafer track for oriented wafer 40 for ultimate discharge into chute 22.

It will be noted that the upper corners of the window 32a-32h are asymmetrically relieved at 36 and 38 in a manner complementary to the position of the wafer as shown in FIG. 1. The individual stations 32a and 32h are arranged in a manner such that when a wafer passes by a window it will rotate 90° by going over the step between adjacent tracks 26. A inversion station 46 is provided between station 26d and 26e. This inversion station 46 is best shown in FIG. 6, and comprises an enlarged aperture 48 which causes all wafers passing thereby to fall therewithin so as to be discharged in a 180° inverted position through the second aperture 50 at the bottom of the inversion station. The wafers then continue down through stations 26e through 26h until they fall

through the appropriate window which indicates by said passing that the wafer has been oriented.

As best shown in FIG. 3, a non-oriented wafer (for purposes of illustration only) is in the position of being 5 180° rotated from left to right as compared to the wafer position shown in FIG. 1. This wafer will pass by the window 32 without falling therethrough and is always supported in such a manner that it cannot jam. More particularly the relieved leading edge adjacent to the top 10 of the wafer, engages the margin of the window adjacent to the corner 36 prior to the trailing wafer edge at 14 leaving the margin of the window adjacent to corner 38. This, of course, is also true of the wafer when it is in any 15 of the other six remaining non-oriented positions relative to the window 32.

In some instances it is desirable to have the vibrating 20 mechanism 24 which powers the orienting feeder mechanism automatically actuated in terms of desired output of the feeder. To this end the discharge chute 22 may be provided with the electric photo cell means 42 and 44 which are connected in the circuit with the vibrator mechanism 24.

From the foregoing description it will be apparent that 25 a novel method of configuring a wafer and an orientation means therefor have been provided which are particularly well adapted for use with small sized wafers. Although a specific embodiment has been shown and described, it is with full awareness that many modifications thereof are possible. The invention, therefore, is not to be 30 restricted except in so far as necessitated by the prior art and by the spirit of the appended claims.

What is claimed as the invention is:

1. In orienting apparatus for flat thin generally square articles having asymmetrically relieved corners adjacent 35 one edge only of the articles comprising supporting inclined framework, windows in said framework having a generally rectilinear configuration with a height less than the dimension of a side of said articles, the upper two corners of said window being asymmetric in configuration and of lesser dimension than square, complementary to and slightly larger than the configuration of said articles only when oriented in a single position of eight possible 40 positions, the material of the framework in the asymmetrical corners preventing non-oriented articles from falling through said windows, and vibrator means for said framework to move said articles past said windows for orientation thereof.

2. In orienting apparatus for flat thin generally square articles having triangularly asymmetrically relieved 50 corners adjacent on edge only of the articles, comprising supporting inclined framework, windows in said framework having a generally rectilinear configuration with a height less than the dimension of a side of said articles, the upper two corners of said windows being asymmetric in 55 configuration and of lesser dimension than square, said two corners being generally angular in configuration and having a marginal edge corresponding to and slightly larger than the hypotenuse of the triangular relief of the wafer to be oriented, said windows being complementary to and slightly larger than the configuration of said articles only when oriented in a single position of eight possible 60 positions, the material of the framework in the asymmetric corners preventing non-oriented articles from falling through said windows, and vibrator means for said framework to move said articles past said windows for orientation thereof.
